CEILING

Shirley R. Naysmith and Richard M. Runge, Meriden, Conn., assignors to The Miller Company, Meriden, Conn., a corporation of Connecticut

Application September 7, 1945, Serial No. 614,932

9 Claims. (Cl. 189—85)

1

The present invention relates to ceilings and is more particularly directed toward hung ceilings adapted to include wherever desired in the ceiling, inbuilt or flush mounted lighting equipment.

In practicing the present invention it is possible to employ common suspension means for both the surfacing material of the ceiling and the wiring channels of the lighting equipment in such a manner that the suspension means supports either the ceiling surfacing material alone or the wire channels alone or both ceiling and wiring channels, as more fully discussed in Patent 2,376,715, May 22, 1945.

The present invention contemplates improved yokes for use in such ceiling constructions of increased rigidity and with improved facilities for supporting the wiring channel of the lighting fixture from the yoke as well as for the securing of the yoke to the hanger by which it is suspended. The invention also contemplates improvements in the yoke per se which facilitates securing to it the T-bar used in common forms of acoustical ceiling.

Other and further objects will hereinafter appear as the description proceeds.

The accompanying drawings show, for purposes of illustrating the present invention, two embodiments in which the invention may take one form, together with modifications of certain parts, it being understood that the drawings are illustrative of the invention rather than limiting the same.

In these drawings:

Figures 1 and 2 are perspective views taken from above, of hung ceilings adapted to receive recessed lighting equipment, showing different arrangements for supporting the ceiling and wiring channels;

Figure 3 is a fragmentary view illustrating a clamp hanger for a wiring channel;

Figure 4 is a top plan view of one form of hanger yoke used for supporting both the hung ceiling and the wiring channel or either;

Figure 5 is a side elevational view of the hanger yoke of Figure 4;

Figures 6 and 7 are transverse sectional views on the lines 6—6 and 7—7 on Figure 5;

Figure 8 is a longitudinal sectional view on the line 8—8 of Figure 4;

Figure 9 is a perspective view of one of the clamping members detached;

Figure 10 is a top plan view of another form of construction;

Figure 11 is a side elevation of the structure of Figure 10; and

Figure 12 is a fragmentary elevational view illustrating a modified form of construction.

In the arrangements shown in Figures 1 and 2, hanger rods 10 are secured to the structural ceiling

2

ing not shown in suitable spacings. Where tiled ceilings are employed the spacing of the rows of hanger rods is such as to accommodate the tiles. The spacing of the hanger rods lengthwise of the rows depends upon the structural layout and where lighting equipment is to be or may be employed. Each of the hanger rods 10 of Figures 1 and 2 is secured to a suitable hanger.

The hanger shown in Figures 4 to 9 employs a hanger strap 11 of inverted U-shape with a slot 12 to receive the hanger rod and with feet 13, secured to bolts 13' welded to a hanger yoke 14. This yoke is made out of steel of channel-shaped cross-section and is bent into an inverted U-shape as will be apparent from the drawings. The web 14a of the channel is provided with an aperture 15 (see Figure 8) through which projects a lug 16 formed out of the hanger strap 11. This lug is provided with a tapped hole to receive a bolt 17.

The yoke 14 receives two clamping members 18 and 19 which for convenience in manufacture, are made alike and are shown more clearly in Figure 9. Each clamp member is made out of channel-shaped stock, provided with an opening 20 of the proper size to permit sliding a clamping member along the channel forming the yoke 14. The material punched out to form the opening 20 provides two welding lugs 20a which fit outside the yoke. The opening 20 is so located that the upper flanges 21 of these clamping members fit the top of the flanges 14b of the yoke 14 and then the lower flanges 22 of the clamping members are then spaced below the web 14a of the yoke 14. Each clamping member has a downwardly bent lug 23 formed out of the material of the lower flange 22 and this downwardly bent lug is provided with a hole 24. The cut-out of this lower flange provides a slot or opening in it which accommodates the lug 16 so that the edges of the flanges 22 of the right hand clamping member may be forced against the bead of the wiring channel by the bolt 17.

The clamping member 18 on the left hand side of Figures 4, 5 and 8, is brought against a positioning lug 25 and the welding lugs 20a are spot welded to the yoke as indicated at 26. It, therefore, provides a fixed abutment for the bead 27 along the left hand side of the wiring channel 28. The member 19 on the right is loose and the bolt 17 is used to force the clamping member to the left and press its lower flange 22 under the bead 27a on the right hand side of the wiring channel 28. Twisting is prevented by the top flange 21 riding along the edges of flanges 14b. In this manner the wiring channel can be secured to all the yokes 14 in a row of yokes wherever lighting equipment is desired.

The lower ends 30, 30 of the yokes 14 are provided with slots 31, 31 cut in the flanges 14b, 14b

and a portion of the material of the flange below these slots is removed as indicated at 32. These slots are at the right elevation to receive the side flanges 33 provided in the T-bar 34 commonly employed for the support of acoustic ceilings. The T-bar is secured in place by clamp straps 35 and bolts 36, and cannot twist out of place.

The yokes illustrated in detail in Figures 4 to 9 are of the proper width to space the T-bars 34, 34 the distance to receive a ceiling tile which closes off the space underneath the row of yokes where no lighting fixture is desired. Where, however, the lighting equipment is desired the wiring channel can be secured in place in a very rigid manner by the clamping devices shown. As the hanger strap is securely bolted to the hanger yoke and one of the clamping members is welded to the yoke and the load of the lighting equipment is transferred directly to the hanger strap, the entire structure is extremely rigid and unlikely to be distorted under any load which can conceivably be placed upon it.

In a ceiling installation such as shown in Figure 1, the hanger rods 10 with straps 11 and yokes 14 are spaced suitably about the ceiling area so as to support all of the ceiling itself and provide supports for wiring troughs wherever fixtures are desired. The yokes support the T-bars 34 alongside them as above described. They also support suitable longitudinally extending angle members 35 which in turn support cross-channels 36 so that other additional T-bars 34 may be carried, if desired and in this way supports are provided in all the ceiling surfacing material for the entire ceiling. The wiring channel and fixtures may be secured to the yokes before or after the ceiling is installed and the ceiling can be installed before or after the fixtures. Any form of tiled or plastered ceiling may be carried from the hangers.

Figure 2, shows a somewhat similar installation but here the hanger rods and yokes are spaced farther apart and intermediate yokes 14' are installed for the purpose of holding the ceiling framework together and providing an intermediate support for wiring channel. Such a yoke 14' may be the same as the yoke 14 except that it does not have the hanger strap 11. Instead it is provided with welded lug 16' (see Figure 12) similar to the lug 16 previously described. The clamping member 19 and bolt 17 may be the same as above set forth.

In some instances it is also desirable to support the wiring channel directly from a hanger rod without having any yoke and in this case one uses a hanger such as illustrated at 37 in Figure 3. When the wiring channel is supported by a hanger such as 37, yokes such as 14' may be used elsewhere to support the ceiling from the wiring channel. Where it is desired to have the T-bars such as 34' extend at right angles to the direction of the wiring troughs, the yokes are secured to the channels such as indicated at 38 and these channels carry the T-bars.

In the arrangement shown in Figures 10 and 11, the hanger strap 11' differs from the one shown in Figures 4-8 in that it is arranged for welding directly to the yoke and it does not have a downwardly extending lug 16. The yoke 40 is very similar to the yoke 14 above described. The clamp members 41 and 42 are alike and made out of channel stock. The yoke 40 is provided with a lug 43 similar to the lug 25. The channel 41 is provided with a reversely bent prong 44 to fit under the yoke and the channel 41 is welded to the yoke in the location indicated. The clamping member 42 is slidable along the yoke and

bolts 45 are employed to force the slidable clamp toward the fixed clamp. The extent to which the slidable clamp can move to the left is limited by the prongs 44 bumped out of the material forming the flange of the yoke. The arrangement shown in Figures 10 and 11 functions in general the same as the construction shown in Figures 4 to 9.

Since it is obvious that the invention may be embodied in other forms and constructions within the scope of the claims, we wish it to be understood that the particular forms shown are but a few of these forms, and various modifications and changes being possible, we do not otherwise limit ourselves in any way with respect thereto.

What is claimed is:

- Means for supporting a suspended ceiling and a lighting fixture wiring channel having beads along its upper edge, comprising an inverted U-shaped ceiling hanger yoke having means at its lower ends for the support of the suspended ceiling, and means carried by its upper central portion for supporting the wiring channel, said latter mentioned means including a fixed clamp member and a slidable clamp member carried by the hanger yoke on opposite sides of the center thereof, the clamp members being in the form of channels each having an aperture in the web portion thereof to fit the yoke and disposed to place the top flange of the clamp member against the upper edges of the sides of the yoke and the lower flange of the clamp member below the yoke in a position to enter the bead of the wiring channel, and bolt means for forcing the clamp members toward one another.
- Means for supporting a ceiling and a wiring channel as claimed in claim 1, wherein the lower ends of the yokes have slots to receive the side flanges of ceiling T-bars.
- Means for supporting a ceiling and a wiring channel as claimed in claim 1, having inverted U-shaped hanger straps above the centers of certain of the yokes and welded to them.
- Means for supporting a ceiling and a wiring channel as claimed in claim 1, wherein the last mentioned means includes two bolts extending from one clamp member to the other and alongside the hanger yoke.
- A device for supporting the longitudinal members of a hung ceiling and a lighting fixture wiring channel having longitudinally extending beads along its upper edge, comprising a bar of channel cross-section bent into an inverted U-shape with a horizontal top and vertical sides, the latter having means to support the hung ceiling, the top having downwardly bent fixed lugs spaced wider than the beads of the channel, two clamp members each of channel cross-section apertured to slide along the yoke and of a size such that the upper flanges of the clamp members fit the top of the flanges of the yoke, and the lower flanges are spaced below the web of the channel forming the yoke, one clamp member being welded to the yoke with its web against one lug and its lower flange facing inwardly to form a bead receiving abutment and a bolt securing the other clamp member to the other lug with the lower flange of this clamp member facing inwardly to engage the other bead of the wiring channel.
- A device as claimed in claim 5, having inverted U-shaped hanger straps above the centers of certain of the yokes and welded to them.
- In combination, a ceiling supporting yoke of inverted U-shaped configuration and channel

shaped cross-section with the web of the channel 15
interiorly disposed, the yoke having a downwardly bent positioning lug and a downwardly bent lug having a threaded hole, a slidable clamp member apertured to receive the yoke and having an upper flange overlying the edges of the flanges of the yoke, a lower flange spaced below the web of the yoke, and an apertured lug opposite the threaded hole, a second clamp member of similar contour to the first and welded to the yoke with its web against the positioning lug with its lower flanges facing inwardly, and a clamping bolt threaded into the hole for forcing the first clamp member inwardly.

8. An inverted U-shaped ceiling hanger yoke 20
of channel shaped cross-section having means at its lower ends for the support of a suspended ceiling, and means carried by its upper central portion for supporting a wiring channel having side beads along its upper edge, said latter mentioned means including a positioning lug bent downwardly out of the channel web, a second downwardly extending lug fixedly secured to the channel web and provided with a tapped hole, two clamp members of channel shaped cross-section each having an aperture in the web portion thereof to receive the yoke and slidably from the end of the yoke toward one of the lugs, the lower flanges of the clamp members being spaced 25
below the web of the channel forming the hanger

yoke, one clamp member being welded to the hanger yoke alongside the positioning lug, the other clamp member having a cut-out in the lower flange to accommodate the second lug and a bolt hole opposite the threaded hole in the second lug, and a bolt passing through the bolt hole and threaded into the threaded hole.

9. Means for supporting a ceiling and a wiring channel as claimed in claim 1, having inverted U-shaped hanger straps above the centers of certain of the yokes and welded to them, and wherein in one end of the hanger straps extends downwardly through an opening in the yokes and has a tapped hole for the bolt means.
